Inventor:

August Zoeller.

By *William Taubert*

Attorney.

UNITED STATES PATENT OFFICE.

AUGUST ZOELLER, OF SACRED HEART, OKLAHOMA.

MULTIPLE-SECTION REMOVABLE SCREEN FOR COTTON CLEANERS.

Application filed July 23, 1924. Serial No. 727,732.

To all whom it may concern:

Be it known that AUGUST ZOELLER, a citizen of the United States, residing at Sacred Heart, in the county of Pottawatomie and 5 State of Oklahoma, has invented certain useful Improvements in Multiple-Section Removable Screens for Cotton Cleaners, of which the following is a specification, reference being had therein to the accompanying drawing.

In most cotton cleaners and boll breakers now on the market, and especially the Munger type, the screen for the spiked cylinder beaters or cleaners is in one piece, 15 there being a screen concave for each cylinder beater or cleaner, and it has been found, in practical experience, that this construction and arrangement involves the disadvantage of requiring the entire screen to 20 be removed in case of needed repairs or an entire new screen substituted. In other words, should any one of the screen concaves become damaged, the entire screen must be removed to make the repairs and 25 if beyond repairing a whole new screen must be installed.

The present invention has for its purpose to provide a multiple section screen and, obviously, in this case should any one 30 of the concaves of any one of the sections be damaged, it may be removed without disturbing the others to permit of repairs and if repairs are not possible, a new section may be inserted instead of the old section. 35 Another purpose is to provide a screen for the spiked cylinder beaters wherein the sections thereof may be slid into and out of place, there being in conjunction with the multiple section screen an angle frame 40 adjustably supported in a chamber under the cylinder beaters so that either one of the sections of the screen may be individually removed, it being possible to either repair the section or substitute a new one 45 without disturbing or disposing of the remaining sections.

Still another purpose is to provide, in a cotton cleaner and boll breaker, an arrangement of concave screen sections which are 50 easily reached by lowering the supporting frame (which constitutes a floor for the compartments in which the cylinder beaters are operable), there being means at the ends of the frame for supporting the same 55 in said compartment. When the support-

ing frame is lowered, one end protrudes through the door in the casing of the cotton cleaner and boll breaker, the frame being disposed in an inclined position to accomplish this result so that any one of 60 the sections may be separately removed.

A further purpose is to provide an adjustable hinge at the inner end of the supporting frame, so that the innermost screen section may be removed and allowed to 65 slide down the frame without interference with the innermost cylinder beater.

It is to be understood that the particulars herein given are in no way limitative and that, while still keeping within the 70 scope of the invention, any desired modifications of detail and desired proportions may be made in the apparatus according to the circumstances.

The invention comprises further features 75 and combinations of parts to be hereinafter set forth, shown in the drawings and claimed.

In the drawings:

Figure 1 is a view in side elevation of a 80 portion of a cotton cleaner and boll breaking machine, showing the improved multiple section screen applied in accordance with the invention.

Figure 2 is a sectional view through a 85 part of the cotton cleaner and boll breaking machine, more clearly showing the arrangement and supporting of the angle iron frame, also illustrating the adjustable rod.

Figure 3 is an enlarged detail perspective 90 view of one of the screen sections.

Figure 4 is an enlarged detail view of the supporting frame for the screen sections.

Figure 5 is a sectional view through the 95 pivoted end of the angle iron frame 4, showing the rod 5.

Figure 6 is a detail sectional view showing how the wedges are held in position.

Referring to the drawings, 1 designates 100 the frame of the cotton cleaner and boll breaker having a compartment 2 wherein a plurality of spiked cylinder beaters or cleaners 3 are mounted, and 4 denotes a supporting frame for the screen. This frame at its inner end is operatively mounted upon an adjustable rod 5 and is constructed of angle iron and mounted in the lower part of the compartment 2. The frame 4 is so mounted that when it is low- 105 110

ered in an inclined position, its end remote from the adjustable rod mounting 10 protrudes through the door opening 6 of the cotton cleaner machine frame.

- 5 The adjustable rod 5 may be placed in any one of the plurality of apertures 5^a to support the frame 4 in different positions. Cleats 13 are mounted upon the inner 15 faces of the sides of the cleaner and boll breaking machine frame by means of bolts 14 which may enter any of the apertures or openings 15 to hold the cleats in different positions according to the adjustment of the pivot rod 5. Suitable wedges 16 are 20 supported upon the cleats and these wedges, in turn, support the frame 4 which, in turn, supports the screen sections 10 of the screen 9. Each section of the screen 9 consists of a frame 11 provided with a screen concave 25 with and conform to the shape of the cylinder beaters, as shown clearly in Figure 2. 12. When these screen sections 10 are in position, the screen concaves are concentric with and conform to the shape of the cylinder beaters, as shown clearly in Figure 2.
- The cleaner and boll breaking machine 25 frame has a door 6 hingedly mounted, as shown, for closing the frame of the machine when the screen 9 is in an operative position. When the latch of the door 6 is released and the door opened, the wedges 30 16 may be slid out through the door opening, in which case the frame 4 will tilt downwardly on its adjustable pivot rod 5, so that the sections 10 of the screen 9 may be removed for repairs and others inserted. 35 The wedges 16 are secured in position by means of suitable set-screws 17, more clearly shown in Figure 6. When the wedges 16 are removed by detaching the set-screws and the frame 4 lowered, said 40 frame will project partly through the door opening.

Obviously, it is possible to have a number of these screen sections with each cotton cleaner and boll breaking machine so 45 that, in removing any one of the screen sections for repairs, one of the additional screen sections may be substituted for the damaged section, provided repairs to the section are impossible. However, if the 50 screen section can be repaired and the time required to make the repairs is extremely long, a new section may be substituted while the old section is being repaired, obviously saving considerable time in operating the machine. It will be noted that 55 the screen sections may be easily and very quickly inserted and removed, there being no extra space necessary in the back of the frame of the machine for mounting of the 60 screen sections.

The invention having been set forth, what is claimed is:

1. In a cotton cleaning and boll breaking machine, the combination with a frame 65 provided with a compartment wherein a

plurality of spiked cylinder beaters is operatively supported, of a multiple frame screen, each screen frame having a screen concave conforming to and cooperating with the cylinder beaters, and means operatively supported in the lower part of the chamber to support the screen frames in position, said means consisting of a supporting frame with its innermost end operatively detachably supported in said chamber, said supporting 75 frame adapted to be inclined downwardly with its other end protruding partly through an opening in the machine frame, whereby any one of the screen frames may be separately removed.

2. As an article of manufacture, a multiple frame screen and a support therefor for a cotton cleaner and boll breaking machine, the screen frames being arranged in consecutive order in the lower part of a 85 cleaning chamber of the cotton machine, the screen frames being individually removable, and a supporting frame having adjustable and detachable holding means for holding said supporting frame in a raised 90 position to support the screen frames.

3. In a cotton cleaning and boll breaking machine, the combination with a frame provided with a compartment wherein a plurality of spiked cylinder beaters is operatively supported, of a screen supporting frame, means for adjustably and pivotally supporting said screen supporting frame below the cylinder beaters, individual screen sections on the supporting frame, and removable wedges operatively mounted on the sides of the boll breaking machine frame for retaining the screen supporting frame in position.

4. In a cotton cleaner and boll breaking 105 machine, the combination with a frame provided with a chamber with a plurality of spiked cylinder beaters supported therein, of a multiple frame screen, each with a screen concave conforming to a beater, a 110 frame with one end supported within the cleaner frame, whereby the other end may swing downward, said frame screens being in separable arrangement, allowing the frame screens to be individually removed 115 when one end of the supporting frame is lowered, and means for holding the supporting frame in a raised position, whereby the concaves of the screen frames may conform to the beaters.

5. In a cotton cleaner and boll breaking machine, the combination with a frame provided with a chamber with a plurality of spiked cylinder beaters supported therein, of a multiple frame screen, each with a screen concave conforming to a beater, a 125 frame with one end supported within the cleaner frame, whereby the other end may swing downward, said frame screens being in separable arrangement, allowing the 130

frame screens to be individually removed when one end of the supporting frame is lowered, and means for holding the supporting frame in a raised position, whereby the concaves of the screen frames may conform to the beaters, said last named means and the supporting frame being adjustable to support the frame screens in different positions for increasing or decreasing the spaces between the concaves and the beaters. 10

In testimony whereof he affixes his signature.

AUGUST ZOELLER.
